UNITED STATES PATENT OFFICE.

WILLIAM FRANKLIN CARTER, OF PRESCOTT, KANSAS.

COMBINATION AIRSHIP AND AIRPLANE.

Application filed October 11, 1921. Serial No. 507,135.

To all whom it may concern:

Be it known that I, WILLIAM FRANKLIN CARTER, a citizen of the United States, and resident of Prescott, in the county of Linn, State of Kansas, have invented a new and useful Combination Airship and Airplane, of which the following is a specification and description.

My invention relates to improvements in flying machines, particularly to that type known in the art as helicopters.

The object of my invention is to provide a machine of the character described, in which the sustaining planes are provided with means whereby they are moved with respect to the operating platform of the machine and that the axis of the said planes may be adjusted to regulate the ascent, travel, and descent of the machine.

A further object of my invention is to provide automatic means for increasing the air resistance as the machine descends.

Another object of my invention is to provide a machine of the character described having means whereby the same may settle freely upon land or sea, without injury to its structure or passengers.

With these further objects in view I have provided a flying machine embodying novel features of construction and combination and arrangement of parts such as those described and illustrated in the accompanying drawings.

Figure 1 is a rear elevation of the machine showing the planes and lifting means arranged in a vertical position.

Figure 2 is a side view of the same.

Figure 3 is a side elevation of the machine showing the planes and propelling means arranged in a horizontal position.

Figure 4 is a sectional view taken on the line 4—4 of Fig. 3.

Figure 5 is a sectional view of the means for increasing the resistance on the downward movement of the machine.

Figure 6 is a top plan view of the same.

Figure 7 is a detailed sectional view of the same.

Figure 8 is a detailed view of the shaft for supporting the planes, and

Figure 9 is a detailed view of the means for locking the planes in a predetermined position.

Referring to the drawings, in which similar characters of reference denote corre-

sponding parts in the several views, the numeral 1 designates a suitable platform of the machine having arranged on its under portion an air inflated float 2 while on its upper portion affords a passenger seat 3, the same being surrounded by a protecting railing 4. In order to reduce the resistance of the machine in its upward movement the platform 1 is provided with a central opening the same having arranged therein a protecting network, 5.

Arranged on the upper portion of the platform 1 and extending vertically thereto are spaced uprights 6 and 7, the upper ends of which have rotatably mounted therein a shaft 8, as disclosed in the Fig. 8, the outer ends of which have secured thereto suitable sustaining planes 9.

The shaft 8 on its intermediate portion, that between the uprights 6 and 7, has movably mounted thereon a platform 10 upon which is mounted a cylindrical casing 10 the end of which, adjacent the shaft is open while the outer end is provided with automatic closing means which will be further described hereinafter.

The outer end of the casing 10 has therein a bar 11 through the central portion of which passes the propeller carrying shaft 12, the same being operated by a suitable motor, as designated at A, mounted upon the platform 10 in any suitable manner.

The casing 10 has further provided thereon an arm 13 within which is mounted an oscillating shaft 14 the lower end of which is journaled on the platform 10, the upper end of which carries a suitable guiding rudder 15. The shaft 14 is provided with an operating lever 16 by which the lever 15 may be moved so as to direct the machine in its travel.

In order that the sustaining planes may be held in any desired position I have provided on the upper end of the upright 6 a ratchet which is adapted to be engaged by a lever 18 the end of which is pivotally mounted upon a squared portion of the shaft 8, adjacent the upright 6. The lever 18 carrying a plate adapted to engage the ratchet 17 when the latter is swung upon its pivot.

In order that the axis of the propeller may be varied with respect to the sustaining planes and platform I have provided a similar locking element on the upright 7, as indicated at 19 the same being engaged by a

lever 20 pivoted to the platform 10 in any suitable manner and carrying an element adapted to engage the ratchet 19.

As previously referred to the upper end 5 of the cylinder 10 is provided with a pair of hinged doors 21 and 22 hinged to the cross bar 11, in such a manner that they will open as the machine moves upwardly thus reducing the air resistance and close as the machine descends, thereby increasing the air resistance.

Briefly stated the operation of the machine is as follows:

To control the ascent of the machine, I 15 have, as heretofore described, pivotally mounted the shaft carrying the planes in such a manner so the planes may be swung to a position as that indicated in Figure 2 and as also previously described, similar operating means whereby the propeller may be 20 oscillated upon the shaft 8 until it assumes a position similar to that indicated in Fig. 2. When in this position it is evident that as the propeller rotates the machine is caused 25 to move vertically. When the same has reached the proper height the planes, together with the propeller, are swung to the position, by the levers 18 and 20, until they assume the position similar to that indicated 30 in Fig. 3 which will thus direct the machine in a horizontal line of travel. As the machine moves upwardly the doors 20 and 21 will open thereby reducing the air resistance and due to the fact that the platform 1 is 35 provided with an air passage the resistance of the machine is further reduced as it moves upwardly.

In order to descend, the planes and propeller of the machine are swung to a position similar to that indicated in Fig. 2 and 40 as the machine moves downwardly the doors 21 and 22 close thereby increasing the air resistance and retarding the downward movement of the machine.

Having thus fully described my invention, 45 what I claim as new and desire to secure by Letters Patent is:—

1. In a flying machine, the combination of a platform and supports rising therefrom, a shaft revolubly mounted upon said supports, wings carried by the ends of said shaft, means for holding said wings at any angle with respect to said platform, an engine support mounted upon said shaft and between said supports, a propeller mounted 50 upon said engine support and driven by said engine, and means for holding the engine support at any angle with respect to said platform and wings.

2. In a flying machine, the combination of 60 a platform and supports rising therefrom a shaft revolubly mounted upon said supports, wings carried by the ends of said shaft, means for holding said wings at any angle with respect to said platform, an engine 65 support mounted upon said shaft and between said supports, a propeller mounted upon said engine support and driven by said engine, means for holding the engine support at any angle with respect to said wings 70 and means carried by the platform for increasing or decreasing the air resistance upon the descent or ascent of the machine.

WILLIAM FRANKLIN CARTER.
